TRIP DEVICE FOR CIRCUIT BREAKER

Thomas W. Butler, Jr., Ann Arbor, Mich., assignor to
Mechanical Products, Inc., Jackson, Mich., a corpora-
tion of Delaware

Filed Dec. 8, 1965, Ser. No. 512,440

3 Claims. (Cl. 200—116)

This invention relates generally to electric circuit breakers, and more particularly to an improved trip device for an electric circuit breaker.

Automatic electric circuit breakers generally comprise a pair of separable contacts, a releasable operating mechanism that effects separation of the contacts, and a trip device responsive to predetermined electrical conditions in an electrical circuit to effect release of the operating mechanism.

Generally, the trip device comprises a latch mechanism and a current responsive element that effects movement of the latch mechanism to a release condition. Both of these components must satisfy certain basic requirements in order that the circuit breaker be positive in operation, durable, and consistent in performance.

The latch mechanism should have a relatively large latch overlap to preclude spurious unlatching due to, for example, vibration, yet must unlatch the operating mechanism upon relatively slight movements of the current responsive member. The current responsive member must be sensitive to relatively slight current variations above a specific predetermined level and have a usable mechanical response characteristic.

It has long been a problem to produce a relatively inexpensive and compact trip device for a circuit breaker of relatively low current rating having a significant mechanical response characteristic or displacement yet be responsive to relatively small overloads.

An improved trip device for a circuit breaker, in accordance with the instant invention, exhibits a relatively large mechanical displacement due to relatively minute elongation of an electrically conductive wire having a positive temperature coefficient of expansion. The wire is mechanically connected to a rotatable beam in such a manner that an incremental elongation of the wire permits a substantial movement of a latching face on the beam in a direction substantially normal to the longitudinal axis of the wire. The geometry of the trip device is such that friction is minimized between the relatively moving parts, calibration is easily achieved, and reliability is maximized.

Accordingly, one object of the instant invention is an improved trip device for a circuit breaker.

Another object is a trip device having a large mechanical response due to relatively small overload currents.

Other objects and advantages of the present invention will become apparent from the following description taken in conjunction with the accompanying drawings, wherein:

FIGURE 1 is a side elevational view of a single pole circuit breaker with one side of the housing therefor removed;

FIG. 2 is a view of the trip device removed from the circuit breaker;

FIG. 3 is a view taken in the direction of the arrow of FIG. 2; and

FIG. 4 is a view taken in the direction of the arrow 4 of FIG. 2.

As best seen in FIGURE 1 of the drawings, an electric circuit breaker 10 comprises an insulating housing 12 molded from, for example, Bakelite. A pair of terminals 14 and 16 extend from the housing 12 for connection to opposite sides of an external electric circuit.

The terminal 16 extends inwardly of the housing 12

2

for the support of a fixed contact 20. A movable contact 22 is aligned and engageable with the fixed contact 20 to complete an electrical circuit through the circuit breaker 10 comprising the terminal 16, the fixed and movable contacts 20 and 22, a pigtail 24, a current responsive trip device generally designated by the numeral 26, pigtail 28 and the opposite terminal 14.

The operating mechanism for the circuit breaker 10 is conventional in construction and, in brief, comprises a manual operator or plunger 29 that extends externally of and is slidably supported by the housing 12 for "in" and "out" movement. The manual operator 29 comprises an inner plunger portion 30 having a lower end 31 that extends into a guideway 32 formed in a lower wall 34 of the housing 12. A transversely extending pin 36 is fixedly supported by the housing 12 and extends through a slot 38 in the plunger portion 31 so as to guide the manual operator 29 for reciprocation.

A pin 40 is supported on an upper end portion 42 of the inner plunger 30 and extends through a slot 44 in an outer plunger portion 46 of the manual operator 29. The pin 40 and slot 44 function as a lost motion connection between the inner and outer plunger portions 30 and 46 of the manual operator 29.

The inner plunger 30 has a molded central hub portion 48 that is rigidly affixed thereto for the support of a rotatable latch lever 70, as will be described.

The outer plunger portion 46 of the manual operator 29 extends through a ferrule 49 in a front wall 50 of the housing 12 and has a knob 52 secured thereto. The knob 52 is preferably formed from an insulating material, for example, Bakelite, and is shaped to facilitate manual operation of the circuit breaker 10.

The inner plunger portion 30 of the manual operator 29 is normally resilient urged upwardly, as seen in FIG. 1, by a tensioned coil spring 62 having one end portion 64 connected to the latch lever 70 and an opposite end portion 72 connected to a link member 74 that is pivotally connected to a bell crank 76. The bell crank 76 is pivoted on a pin 78 journaled in bearing plate 80.

The bell crank 76 carries a roller 88 that is normally biased by the spring 62 clockwise into complementary notches 90 and 92 in the inner and outer plunger portions 30 and 46 of the manual operator 29, respectively. The spring 62 is sufficiently strong so that when it is tensioned to the position illustrated in FIGURE 1, it holds the roller 88 in the notches 90 and 92 and thereby restrains the outer plunger portion 46 of the manual operator 29 from movement outwardly of the housing 12 and the inner plunger portion 30 from movement upwardly, as seen in FIG. 1, under the bias of the spring 62.

However, when tension of the spring 62 is relieved upon automatic opening of the circuit breaker 10, as will be described, the inner plunger shaft 30 is released for upward movement under the reduced bias of the spring 62. Movement of the roller 88 outwardly of the notches 90 and 92 is also effected upon upward movement of the outer plunger portion 46 due to manual operation of the circuit breaker 10.

The latch lever 70 is pivotally supported by a pin 100 that extends through the hub 48 on the inner portion 30 of the manual operator 29. The latch lever 70 has a latching surface 102 thereon that overlies a complementary latching surface 104 on the trip device 26, to be described.

Upon disengagement of the latching surfaces 102 and 104 on the latch lever 70 and trip device 26, respectively, the latch lever 70 rotates counterclockwise to carry the movable contact 22 out of engagement with the fixed contact 20, thereby to break an electrical circuit through the circuit breaker 10. It is to be noted that the movable contact 22 is mounted on a contact carrier 105, a spring

106 effecting a downward bias thereon relative to the latch lever 70 to provide contact pressure.

In accordance with the instant invention the trip device 26 comprises a generally U-shaped frame 110 defined by a bight portion 112 and spaced leg portions 114 and 116. The leg portions 114 and 116 have circular studs 118 and 120 thereon, respectively, for acceptance in complementary circular sockets (not shown) in the housing 12 of the circuit breaker. The rotative position of the frame 110 relative to the housing 112 is controlled by a calibration screw 122 (FIG. 1) that is engageable with an upstanding flange 124 on the frame 110.

A generally U-shaped beam 130 defined by a bight portion 132 and spaced leg portions 134 and 136 is pivotally secured to the leg portions 114 and 116 of the frame 110 by a pin 138. The pin 138 extends through the leg portions 114 and 116 of the frame 110 at points intermediate the studs 118 and 120 and the bight portion 112 thereon.

A trip device spring 140 is secured to the beam 130 as 20 by a pair of rivets 142 and 144, an end portion 146 of the spring 140 having a portion 147 that extends through a complementary aperture 148 in the bight portion 112 of the frame 110 to exert a clockwise bias on the beam 130 relative to the frame 110 as seen in FIG. 2 25 of the drawings.

Rotation of the beam 130 relative to the frame 110 is controlled by a current responsive extensible wire 150, an upper end portion 152 of which is secured to the bight portion 112 of the frame 110 and a lower end portion 30 153 of which is secured to an insulating grommet 154 which in turn is secured to the bight portion 132 of the beam 130. A flexible electrical connector 160 is electrically connected to the end portion 153 of the wire 150 and a flexible electrical connector 152 is connected to the 35 frame 110 to complete an electrical circuit through the trip device 126. A suitable heater 162 is preferably wound about the wire 150 to speed up the response thereof.

A latch bar 170 is secured to a latch bar spring 172 as 40 by a pair of rivets 174. The latch bar 170 contains the latching surface 104, discussed hereinbefore, that supports an end portion 102 of the latch 70. Rotation of the frame 110 under the bias of the spring 140 upon elongation of the wire 150 effects movement of the latch bar 170 to the 45 left as seen in FIGS. 1 and 2 of the drawing to effect release of the latch lever 70. It is to be noted that the latch bar 170 can be biased to the left as seen in FIG. 1 of the drawing, by the end portion 102 of the latch 70 to effect retatching due to the inherent resilience of the 50 spring 172.

Manual operation of the circuit breaker 10 is effected by pulling upwardly on the knob 52 on the outer plunger portion 46 of the manual operator 29. Upward movement of the outer plunger portion 46 effects camming of the roller 88 to the right, as seen in FIG. 1 of the drawings, permitting the inner plunger portion 36 of the manual operator 29 to move upwardly and carry the latch 70 and movable contact 22 upwardly.

The contacts 20 and 22 of the circuit breaker 10 are closed by pushing downwardly on the knob 52 of the outer plunger portion 46.

Automatic opening of the circuit breaker 10 due to an

5 overload or short circuit condition is achieved by elongation of the current responsive wire 150 which permits the beam portion 130 of the trip device 26 to rotate clockwise under the bias of the trip device spring 140. Clockwise rotation of the beam 130 carries the latch surface 104 on the latch bar 170 to the left, as seen in FIG. 2 of the drawings thereby freeing the latch 70 for counterclockwise rotation under the bias of the spring 62 to separate the movable contact 22 from the fixed contact 20. Counterclockwise rotation of the latch 170 reduces the bias of the spring 62 on the bell crank 76 and roller 88 freeing the manual operator 29 for movement upwardly to the contacts open condition.

10 It is to be understood that the specific construction of the improved trip device for a circuit breaker herein disclosed and described is presented for the purpose of explanation and illustration and is not intended to indicate limits of the invention the scope of which is defined by the following claims.

What is claimed is:

1. An electric circuit breaker comprising, a housing, a pair of separable contacts in said housing, a releasable operating mechanism mounted on said housing and operable to effect separation of said contacts, a trip device frame, means adjustably supporting said frame on said housing, a beam pivotally secured to said frame, a latch on said beam engageable with said operating mechanism, resilient means mounted on said beam for normally biasing said beam for rotation relative to said frame, and, a current responsive wire having a positive temperature coefficient of expansion connected to and extending between said frame and beam, elongation of said wire allowing said beam to rotate relative to said frame under the bias of said resilient means to retract the latching surface on said beam from engagement with the operating mechanism of the circuit breaker.
2. A trip device for an electric circuit breaker in accordance with claim 1 wherein; said frame is of generally U-shaped configuration defined by spaced leg portions having a bight portion therebetween, said beam is of generally U-shaped configuration defined by a bight portion and spaced leg portions, the leg portions of said beam being pivotally secured to the leg portions of said frame, respectively, and said current responsive wire is connected to and extends between the bight portions of said frame and beam, respectively.
3. A trip device for an electric circuit breaker in accordance with claim 1 wherein; said resilient means comprises a leaf spring carried by said beam, and, said latch is mounted on said spring so as to facilitate engagement of said operating mechanism therewith.
